ABSTRACT OF THE DISCLOSURE

Strand is advanced at constant linear velocity through a rotating flier tube which distributes the strand into compact layers of spiral convolutions on a nonrotating receiving platform. The rotating flier tube is cyclically operated between conditions of nonlinear angular acceleration and nonlinear angular deceleration by cyclically reversed, nonlinear control of a variable speed transmission. The receiving platform is lowered by the thickness of the strand with each such cyclical reversal and is continuously vibrated to form compact layers of spiral convolutions on the platform.

BACKGROUND OF THE INVENTION

In the art of coiling continuously advancing strand, such as continuously cast and rolled copper rod, as compact a formation of convolutions of strand as possible is desired. A very compact formation may be obtained by coiling the strand into a series of layers of spiral convolutions resting one upon another on a receiver, such as a table or platform. Alternate layers of spiral convolutions may be distributed at continuously increasing laying radius and then at continuously decreasing laying radius to provide the required formation on the receiver.

It is desirable that strand which is advanced continuously at constant speed be distributed in compact spiral layers on the receiver by utilizing a rotating distributor having an exit point through which the advancing strand is passed. The use of a rotating distributor makes unnecessary any rotation of the receiver, which rotation might result in centrifugal forces disrupting the pattern of convolutions previously laid on the receiver.

Additionally, it would be advantageous to orbit the distributor exit point at a fixed radius about the axis of rotation of the distributor to avoid the complex driving arrangements required for rotary plus radial movement of the exit point. Such orbiting might involve varying angular velocity and/or angular acceleration of the rotating distributor according to a predetermined plot, plan or program in order to lay the strand in compact spiral coils.

SUMMARY OF THE INVENTION

An object of the invention resides in new and improved methods and apparatus for distributing strand into spiral convolutions on a receiver.

An apparatus constructed in accordance with the principles of the invention and usable to practice the method of the invention employs a nonreciprocating, rotating distributor, in the form of a flier tube through which strand material is continuously advanced, and a nonreciprocating, nonrotating receiver, in the form of a table or platform for receiving and supporting plural layers of spiral convolutions of strand. Through the use of a novel rotary speed regulating system for varying the angular velocity and angular acceleration of the rotating flier tube with time in a predetermined manner, a compact pattern of layers of spiral convolutions are laid upon the receiver.

The apparatus is set normally to lay each successive

2

convolution of strand just touching the last laid convolution in the same layer. Successive layers of coiled strand are distributed on the receiver in alternate inwardly and outwardly spiraled configurations. The particular position which each element of strand assumes upon the receiver is governed by (1) the angular velocity, angular acceleration and rate of change of angular acceleration of the rotating flier tube at the time of distribution of the strand element and (2) the vertical distance between the flier tube and a reception point of the strand element on the receiver. In order that similar rotary operations of the flier tube produce like patterns of strand distribution in each layer, the vertical distance between the flier tube and the receiver is increased by the thickness of the strand after the distribution of each layer of convolutions. Thus, the vertical distance between the topmost layer of strand on the receiver and the flier tube remains constant during strand distribution and the desired compact pattern of plural layers of spiral convolutions is maintained.

BRIEF DESCRIPTION OF THE DRAWING

FIG. 1 is a plan view of apparatus constructed in accordance with the principles of the invention for distributing onto a receiver a continuously advancing strand in accordance with a desired pattern;

FIG. 2 is a side elevational view, the parts broken away, showing a portion of the strand distributing apparatus of FIG. 1 and also illustrating a receiving and supporting apparatus which is constructed in accordance with the principles of the invention for providing a compact pattern of spiral convolutions of distributed strand;

FIG. 3 is a circuit diagram illustrating a control circuit suitable for operating the apparatus to produce the desired compact pattern of spiral convolutions of strand;

FIG. 4 is a schematic illustration of the desired pattern of strand distribution, constituting one of several layers of compactly distributed spiral convolutions of strand; and

FIG. 5 is a plot of required distributor angular velocity versus both time (solid line) and laying radius (dotted line) describing the distribution of strand from a continuously rotated distributor, included in the apparatus of FIG. 1, through which the strand is advanced at constant linear velocity, in order to produce the desired pattern of FIG. 4.

DETAILED DESCRIPTION

Referring to FIGS. 1 and 2 of the drawing, an apparatus for distributing continuously advanced strand material, such as continuously cast and rolled copper rod 11, is illustrated. For the reason discussed above, i.e., to avoid applying centrifugal forces to the rod or strand already laid, the apparatus includes a continuously rotated distributor or flier tube 12 for laying the strand 11 on a receiver apparatus 13 including a tub or drum 14 on a non-rotating receiver table or platform 16 for supporting coiled strand. The flier tube is mounted for rotation in stationary bearings 15. The strand 11 is continuously advanced through the flier tube 12 at a constant linear velocity by a capstan 17. The capstan is driven by a constant speed rolling mill, such as is shown in Cole et al. application Ser. No. 636,196, filed May 4, 1967, through an input shaft 18, a right angle drive 19, and a shaft 21. The tangential velocity of the capstan 17 is preferably maintained slightly greater than the constant linear velocity of the rod or strand 11 exiting from the rolling mill, in order to produce a slight tension therein.

A pulley 22 is mounted on the distributor or flier tube 12 and is driven by a belt 23 to rotate the flier tube at a continuously varying angular velocity. By varying the angular velocity of the flier tube 12 with time according to a predetermined scheme of operation, a compact pat-

tern of spiral convolutions of strand may be distributed by the flier tube on the receiver apparatus 13. An analysis of the required variation of flier tube angular velocity with time follows.

If the flier tube 12 were rotated at a constant angular velocity, the strand would be laid in successive circular convolutions of identical radius. The constant linear velocity of the advancing strand and the constant angular velocity of the flier tube would determine this effective laying radius.

Should the angular velocity of the flier tube instead be decreased with time, it is clear that a greater period of time would be required to complete each revolution of the flier tube. Since the rod exists from the flier tube at a constant linear speed, a greater length of rod will be delivered per revolution at decreasing angular velocity. Thus, the radius of lay will increase as the angular velocity of the flier tube decreases. Conversely, and by similar reasoning, the diameter of the lay will decrease with an increase in flier tube angular velocity. The instantaneous radius of lay is proportional to the reciprocal of the instantaneous angular velocity.

If the angular velocity is increased at constant angular acceleration, the laying radius will decrease continuously. However, the magnitude of the change in radius for each successive revolution will also decrease continuously, so that adjacent convolutions will begin to overlap. The degree of overlap will become greater as the coil radius decreases. Conversely as the angular velocity decreases and the radius increases, the change in radius for each successive revolution increases resulting in a greater and greater spacing between adjacent convolutions. This effect is due to the fact that the time required to make each successive revolution changes, decreasing as angular velocity increases and increasing as angular velocity decreases. As the time for one revolution decreases, in the case of increasing angular velocity, the angular velocity does not have as long a period to accelerate as it did on the previous revolution and therefore the coil radius does not decrease by an amount equal to the decrease in radius of the previous convolution. Similarly, when the angular velocity is decreasing, a progressively longer period of acceleration occurs with each revolution causing each successive convolution to be further spaced from the previous lay. It is evident, therefore, that means must be provided to progressively increase or decrease the rate of change of the angular velocity, i.e., provide a means for continually changing the rate of angular acceleration and deceleration.

The desired spiral (FIG. 4), having equidistant separation a between each convolution, is of a type known as the Spiral of Archimedes. See Lionel S. Marks, "Mechanical Engineers' Handbook" (sixth edition, McGraw-Hill), pp. 2-61 and 2-62. Referring to the Archimedes' spiral shown in FIG. 4, let:

$r_1, r_2, r_3 \dots$ equal the radii of points on successive convolutions all taken at the same angular position.

$l_{1-2}, l_{2-3}, l_{3-4} \dots$ equal the length of an arc of one convolution between points $r_1-r_2, r_2-r_3, r_3-r_4 \dots$

a equals the distance between the center lines of adjacent convolutions (constant).

$w_1, w_2, w_3 \dots$ equal the instantaneous angular velocity of the flier tube at points $r_1, r_2, r_3 \dots$

v equals the linear velocity of a point on the strand (constant).

$t_2, t_3, t_4 \dots$ equal the total time required to lay arcs $l_{1-2}, l_{2-3}, l_{3-4} \dots$ (considering $t_1=0$).

Knowing the inner and outer diameters of the desired coil of spiral convolutions of strand, the separation between convolutions a are the linear velocity v of the strand, values for angular velocity w can be plotted either as a function of time or of laying radius. This information may then be used to preset the apparatus

of FIGS. 1 and 2 to achieve the desired coil size and spacing between convolutions.

The relation between angular velocity, linear velocity, and radius of a rotating body can be expressed by:

$$v=wr$$

where

$$v=\text{ft./sec.}$$

$$w=\text{radians/sec.}$$

$$r=\text{ft.}$$

Therefore the required instantaneous angular velocity of the flier tube 12 to lay any point on the arc of the spiral, at a distance r feet from the center, may be calculated.

Considering, by way of example only, a specific case wherein a coil having a 3 ft. outer diameter, a 2 ft. inner diameter, and a 0.2 ft. spacing between the center lines of adjacent convolutions is desired and wherein the linear velocity of the strand is 20 ft./sec.:

$$w_1=\frac{v}{r_1}=\frac{20}{3}=6.67 \text{ rad./sec.}$$

$$w_2=\frac{v}{r_2}=\frac{20}{r_1-a}=\frac{20}{3-2}=7.14 \text{ rad./sec.}$$

$$w_3=\frac{v}{r_3}=\frac{20}{r_1-2a}=\frac{20}{3-4}=7.68 \text{ rad./sec.}$$

etc.

The total arc length, l_t of the spiral from its center, 0, to any radius, r , is given by:

$$l_t=\frac{\pi}{a}r^2$$

See Marks' handbook (cited above) at pp. 2-62. Therefore, the arc length of one convolution extending from r_1 to r_2 is:

$$l_{1-2}=\frac{\pi}{a} \times r_1^2 - \frac{\pi}{a} r_2^2 = \frac{\pi}{a} (r_1^2 - r_2^2)$$

$$l_{1-2}=\frac{\pi}{2} (3^2 - 2.8^2) = 18.23 \text{ ft.}$$

Similarly:

$$l_{2-3}=\frac{\pi}{2} (2.8^2 - 2.6^2) = 16.95 \text{ ft.}$$

$$l_{3-4}=\frac{\pi}{2} (2.6^2 - 2.4^2) = 15.71 \text{ ft.}$$

The time required to transverse any arc such as l_{1-2} :

$$t=l_{1-2} \cdot v$$

Considering $t_1=0$ at start of coil:

$$t_2=\frac{l_{1-2}}{v}=\frac{18.23}{20}=.912 \text{ sec.}$$

$$t_3=\frac{l_{1-2}+l_{2-3}}{v}=\frac{18.23+16.95}{20}=1.76 \text{ sec.}$$

$$t_4=\frac{18.23+16.95+15.71}{20}=2.55 \text{ sec.}$$

etc.

Tabulating values for radius, angular velocity, and time at points 1 through 6 we have:

	1	2	3	4	5	6
Radius (ft.)	3.0	2.8	2.6	2.4	2.2	2.0
w (rad./sec.)	6.67	7.14	7.68	8.33	9.08	10.0
t (sec.)	0	.912	1.76	2.55	3.27	3.93

Curves of the angular velocity, w , are plotted against both time (solid line) and radius (dotted line) in FIG. 5, where $t=0$ corresponds to the greatest diameter. The slope of either curve continually increases as it is traced from a point of greater to lesser coil radius indicating a continually increasing angular acceleration. Thus, it may

be observed that during periods of increasing flier tube angular velocity, a laying radius decreasing by uniform separation a between convolutions will occur with increasing angular acceleration. By further analysis of the angular velocity versus time curve of FIG. 5, it may be determined that the rate of increase of angular acceleration with time is nonlinear. Similarly, uniform outward spiraling may be shown to result from rotating the flier tube 12 according to the plotted curves at continuously decreasing angular velocity and continuously decreasing deceleration, the decrease in angular deceleration with time being nonlinear. Tables of data obtained in the above-exemplified manner may be used to determine the required curves of angular velocity versus time necessary for the rotation of the flier tube 12 of FIGS. 1 and 2 in order to produce any desired pattern of uniformly spaced spiral convolutions of strand on the receiving apparatus 13, for example, a pattern wherein adjacent convolutions just touch each other along their edges.

Turning again to FIG. 1, a rotary speed regulating apparatus 26 provides the required speed control to conform the rotation of the flier tube 12 to the calculated curves. A shaft 27 leading from the right angle drive 19 provides an input drive to the speed regulating apparatus 26. A pulley 28 on the shaft 27 drives another pulley 29 through a belt 31. The pulley 29 is mounted to drive an input shaft 32 of a conventional variable speed transmission 30. The input shaft 32 is driven at constant speed, dependent upon the speed of rotation of the shaft 18.

The variable speed transmission 30 may be of a type in which a pair of V-belt, split pulleys 301 and 302 are mounted, respectively, on the input shaft 32 and an output shaft 33. A V-belt 303 extends between the input shaft and the output shaft pulleys. The respective pulley halves of the pulleys 301 and 302, i.e., 301A and 301B, 302A and 302B, are mounted for axial movement to vary the separation between the halves, thereby varying the effective pulley diameters, due to the presence of tapered inner surfaces on the pulley halves. Pulley halves 301A and 302A are both connected to a first lever 304 which is pivotal about a pin 306. Pulley halves 301B and 302B are both connected to a second lever 307 which is pivotal about a pin 308. Each lever 304 and 307 is provided with a pin-like rider 309 which seats within and moves axially along an externally threaded control shaft 34 to pivot the levers, as the control shaft is rotated. The threading on the control shaft is in opposed directions at opposed ends thereof. Thus, rotation of the control shaft 34 in a first direction will, as may be seen by observing FIG. 1, separate the threaded lever ends, spreading apart the pulley halves 301A and 301B and bring the pulley halves 302A and 302B toward one another. Reversed rotation of the control shaft 34 will have an opposite effect upon the separation of the respective pulley halves.

Since the pulleys have tapered inner surfaces to engage the V-belt 303, the spacing between pulley halves determines the effective diameter of each pulley 301 and 302. By rotating the control shaft 34, the ratio of effective diameters of the pulleys 301 and 302 may be varied linearly with the angle of control shaft rotation to vary thereby the speed of rotation of the output shaft 33.

The output shaft 33 rotates the flier tube 12 through a first power train which may be traced from a pulley 41 connected to shaft 33, through a belt 44, through a pulley 42, through a shaft 45, through a right-angle drive 46, through a pulley 43 and then through the belt 23 and the pulley 22.

The output shaft 33 is also connected by a second power train to rotate the control shaft 34. This second power train includes a pulley 47 connected to shaft 33, a belt 48, and a pulley 49 mounted on the input shaft 51 of an auxiliary variable speed transmission 50. The auxiliary variable speed transmission 50 may be of a type similar to the variable speed transmission 30. An output shaft 52

from the auxiliary transmission 50 drives a shaft 53 through a right angle drive 54. A pulley 56 connected to the shaft 53 drives a belt 57 to rotate a pulley 58 on a shaft 59. A pair of oppositely facing bevel gears 62 and 63 are rotatable on the shaft 59. A first clutch 64, engaged by energization of a solenoid 264 (FIG. 3), is operable to provide a drive connection between the shaft 59 and the bevel gear 62. A second clutch 66, engaged by energization of a solenoid 266 (FIG. 3), is operable to provide a drive connection between the shaft 59 and the bevel gear 63. Alternate engagement of the two clutches 64 and 66 enables the bevel gears 62 and 63 to drive a bevel gear 67, constantly meshed with both of the bevel gears, in alternately reversed directions. The disconnected bevel gear 62 or 63 is meanwhile rotated in idling condition upon the shaft 59. The bevel gear 67 is mounted on a threaded shaft 68. A pulley 69 on the threaded shaft 68 drives a pulley 70, mounted on the control shaft 34, through a belt 71.

A reversing mechanism, including a pair of limit switches 72 and 73 mounted adjacent the threaded shaft 68 and axially spaced therealong, is operable to alternately engage one of the clutches 64 and 66 while simultaneously disengaging the other of the clutches. Thus, one of the bevel gears 62 or 63 is driven by the shaft 59 while the other of the bevel gears turns freely thereon, being disengaged therefrom. Alternate engagement of the clutches 64 and 66 to drive alternately the bevel gears 62 and 63, respectively, will rotate the threaded shaft 68 alternately in opposed directions of rotation.

A limit switch actuating disc 74 with an internally threaded central opening is mounted on the threaded shaft 68 to ride axially therealong as the shaft is rotated. A rod 76, parallel to the threaded shaft 68, passes through an eccentric opening on the disc 74 to constrain it against rotation, causing the aforesaid axial movement of the disc upon rotation of the threaded shaft. The limit switch actuating disc will traverse axially along the threaded shaft 68 between the limit switches 72 and 73. As each limit switch is contacted by the disc, the switch functions to alter the condition of engagement of the clutches 64 and 66, thereby reversing the direction of rotation of the threaded shaft 68 and commencing axial movement of the disc 74 back toward the other limit switch. The axial positions of the limit switches 72 and 73 may be made adjustable to afford a means of controlling the inner and outer diameters of a coil to be laid.

The distributing apparatus, as described to this point, will function to alternate the rotation of the flier tube 12 cyclically between a condition of acceleration and a condition of deceleration. As previously explained, the input shaft 32 of the variable speed transmission 30 will be rotated at constant speed by the rolling mill. The control shaft 34 is rotated alternately in opposed directions.

Note that the direction of rotation of the control shaft 34 will affect only the speed, and not the direction, of rotation of the output shaft 33. Assuming for the moment that the auxiliary variable speed transmission 50 is operated to give a fixed speed ratio between the input and output shafts thereof, the speed ratio between the output shaft 33 and the control shaft 34 will remain constant. The output shaft will be rotated alternately at continuously increasing speed and at continuously decreasing speed as the limit switch actuating disc 74 travels back and forth between the limit switches 72 and 73 and the control shaft 34 is rotated at continuously varying speed in alternating directions. Since the belt 23 for rotating the flier tube 12 is driven from the output shaft 33 by the aforementioned first power train, the angular velocity of the flier tube rotation will vary with the speed of rotation of the output shaft 33.

The curve of angular velocity versus time produced by the apparatus, as thus far described, provides only a very rough approximation of the desired solid line curve of

FIG. 5. In order to conform to the FIG. 5 curve much more closely, it has been found desirable to employ the auxiliary variable speed transmission 50 in the drive train between the output shaft 33 and the control shaft 34 of the principal variable speed transmission 30. The auxiliary variable speed transmission 50 is of any conventional type, for example, a type similar to that of the transmission 30, the output speed of which is regulatable by rotation of a control shaft 78. A drive for the control shaft 78 is taken directly from the threaded shaft 68 through pulleys 79 and 81, connected by a belt 82, and a flexible shaft 83 driven by the pulley 82. Thus, the control shaft 78 is operable in similar manner to the control shaft 34 and is rotated at a speed proportional to that of the threaded shaft 68 to accelerate and decelerate alternately the shaft 52, which constitutes the output shaft of the auxiliary variable speed transmission 50. The addition of an acceleration-deceleration operation in the power train between the output shaft and the control shaft of the principal variable speed transmission 30 conforms the performance capability of the distributing apparatus quite closely to the theoretical solid line curve of FIG. 5. The desired curve may be obtained through a proper selection of drive ratios in the various drive trains between the output shaft 33 and the control shaft 34.

Either or both of the variable speed transmissions 30 and 51 may be of other than the type depicted. Among the known variable speed transmissions which are suitable may be included a device wherein parallel, oppositely facing cones are interconnected by an endless belt, adjustable along parallel surfaces of the cones.

Turning now to FIG. 2, a mounting arrangement for the receiving platform or table 16 is shown. This arrangement is designed to maintain constant the vertical distance between an exit point 86 on the flier tube 12 through which the strand 11 is continuously advanced axially and the top layer 87 of convolutions of strand being distributed in the receiving drum 14. By maintaining this vertical distance constant, a uniform laying pattern is preserved for every layer of strand distributed.

A pair of scissor levers 88 and 89, joined together in the vicinity of their longitudinal centers by a pin 91, support the table or platform 16. One end of the lever 89 is joined pivotally by a pin 92 to the receiving platform, while one end of the lever 88, preferably having a supporting roller (not shown) mounted thereon, is transversely movable along a trackway on a bottom surface of the receiving table. The opposite ends of the levers 88 and 89 are, respectively, pinned to and movable transversely on, a supporting base 93. By allowing the scissor lever 88 to pivot about the pin 94 which joins this lever to the supporting base, while the lower end (not shown) of the lever 89 moves along a trackway on the supporting base, the receiving table 16 may be lowered. A cam follower 96 resists the tendency of the lever 88 to so pivot by cooperating with the surface of a cam 97 to bear against the lever. A fluid cylinder assembly 98 maintains the follower 96 against the lever 88 through a piston rod 99. A valve 101, controlled by a solenoid 201, and a manually controlled valve 100 cooperate to adjustably regulate the position of the piston rod 99 by selective exhausting of fluid from the fluid cylinder 98 to control the lowering of the receiving table 16.

To aid further in the distribution of compact layers of spiral convolutions, a conventional pneumatic vibrator 102 vibrates the receiving tub or drum 14 continuously on the platform 16. Springs 103 mount the drum on the platform to permit such vibrating. Undesired buildup of one strand convolution on another adjacent an unfilled gap is prevented by the vibration causing the upper convolution to fall off of the lower convolution and into the gap.

In describing the operation of the strand distributing and receiving apparatus, reference will also be made to FIG. 5, showing a control circuit for the apparatus. It is assumed, initially, that a layer 87 (FIG. 2) of outwardly spiraling strand convolutions has just been laid, that the direction of

rotation of the threaded shaft 68 (FIG. 1) has just been reversed to begin the disc 74 moving away from the limit switch 73 and toward the limit switch 72, and that the receiving platform or table 16 has just been moved downwardly by a distance equal to the thickness of the strand

5

11.

The clutch 64 is now engaged to drive the bevel gear 62 from the continuously rotated shaft 59, thereby driving the bevel gear 67 to rotate the threaded shaft 68 so as to move the disc 74 toward the limit switch 72. The solenoid 264 (FIG. 3) for engaging the clutch 64 is presently coupled across a source of power through a normally closed contact 107-3 of a relay 107, presently not energized. The initial movement of the disc 74 away from the limit switch 73 has returned a contact 73-1 thereof to a normal closed condition and a contact 73-2 thereof to a normal open position, as shown in FIG. 5.

As the threaded shaft 68 is rotated, the control shaft 34 of the principal variable speed transmission 30 and the control shaft 78 of the auxiliary variable speed transmission 50 are rotated from the pulleys 69 and 79, respectively, on the threaded shaft. Note that in the present condition of the principal variable speed transmission 30, as shown in FIG. 3, the ends of the levers 304 and 307 provided with the riders 309 are spaced apart along the control shaft 34 by a distance greater than the spacing between the pins 306 and 308. The halves of V-belt pulley 301 are, therefore, spaced axially apart from each other by a greater distance than that between the halves of V-belt pulley 302. The effective diameter of the driven pulley 302, thus, is greater than that of the drive pulley 301 and the angular velocity of the output shaft 33 is less than that of the input shaft 32.

The threaded shaft 68 and the control shaft 34 rotate in the same direction, as may be seen in FIG. 1. Therefore, the rotation of the threaded shaft 68 which moves the disc 74 toward the limit switch 72 is accomplished by a rotation of the control shaft 34 which moves the riders 309 toward one another. The levers 304 and 307 pivot to increase the effective diameter of the drive pulley 301 and to decrease the effective diameter of the driven pulley 302 as the control shaft continues to rotate. Therefore, the angular velocity of the output shaft 33 begins to increase.

The rotation of the output shaft 33 at increasing angular velocity continues. The continuous increase in angular velocity or acceleration of the shaft 33 is fed back continuously through the power train, including the auxiliary variable speed transmission 50, to rotate the control shaft 34. The riders 309 are drawn together along the control shaft at an increasing rate, varying the effective diameters of pulleys 301 and 302 with increasing speed. This causes a continuously increasing angular acceleration to be imparted to output shaft 33. The operation of the apparatus, as thus far described, provides a good first approximation to the desired solid line curve of FIG. 5.

It should be noted, however, that an additional control of the rotational speed of the output shaft 33 is provided by feedback through the flexible shaft 83 to control the auxiliary variable speed transmission 50 from the threaded shaft 68. The effect upon the principal variable speed transmission 30 of the power train between the output shaft 33 and the control shaft 34 is varied with time as the operative speed ratio through the auxiliary variable speed transmission 50 changes. The combined speed control provided by the two variable speed transmissions 30 and 50 regulates the rotation of the output shaft 33 to orbit the exit point 86 about the axis of the flier tube 12 so as to approximate the solid line curve of FIG. 5. Simultaneously, the capstan 17 continues to advance the strand 11 at constant linear velocity through the exit point 86. An inwardly spiraling layer of strand convolutions, similar to that of FIG. 4, is laid on the receiving apparatus 13.

As the spiral layer is completed, i.e., when a predetermined number of convolutions have been laid, governed by the spacing of the limit switches 72 and 73 and by the pitch of the threaded shaft 68, the disc 74 advances

axially along the threaded shaft 68 to a position whereat the limit switch 72 is engaged. Normally open contacts 72-1 and 72-2 (FIG. 3) are closed through this engagement of limit switch 72. The closing of contact 72-1 completes a circuit through the relay 107, the closed contact 73-1 and the contact 72-1. The relay is energized, operating to close normally open contacts 107-1 and 107-2 and to open the normally closed contact 107-3. The holding contact 107-1 maintains the relay 107 energized so long as the contact 73-1 of limit switch 73 remains closed. The opening of the contact 107-3 de-energizes the solenoid 264 to disengage the clutch 64. The closing of the contact 107-2 energizes the solenoid 266 to engage the clutch 66 and thereby connect the shaft 59 to the bevel gear 63, reversing the direction of rotation of the threaded shaft 68.

The closing of contact 72-2 by the limit switch 72, meanwhile, provides a current path to energize the solenoid 201. The receiving platform control valve 101 (FIG. 4) is thereby operated to start exhausting fluid from the cylinder 98 to lower the receiving platform 16. The exhausting of fluid is terminated upon the reopening of the contact 72-2, deenergizing the solenoid 201. The deenergization of the solenoid 201 occurs upon the disc 74 commencing its return movement away from the limit switch 72 and toward the limit switch 73. The operation of the apparatus is so timed that the contact 72-2 will reopen to stop the downward movement of the receiving table 16 at a position vertically spaced from its previous position by the thickness of the strand 11. The manual flow control valve 100 provides the necessary adjustment capability to so time the operation.

The angular velocity of the rotating flier tube 12 will begin to decrease, changing with time in moving to the left on the solid line curve of FIG. 5. A new layer of outwardly spiraling convolutions of strand, similar to the pattern of FIG. 4, will now be laid on the previous layer 87 at an identical vertical distance from the exit point 86 on the rotating flier tube 12. This will occur as the exit point orbits the axis of rotation of the flier tube.

As the new layer of spiral convolutions is completed, the limit switch actuating disc 74 again engages the limit switch 73. The contact 73-1 (FIG. 3) is opened, de-energizing the relay 107 to open the contacts 107-1 and 107-2 and close the contact 107-3. Now the solenoid 264 is once again energized and the solenoid 266 is deenergized. The direction of rotation of the threaded shaft 68 again reverses and the disc 74 starts traversing back toward the limit switch 72. The contact 73-1 closes as the disc ceases engagement with limit switch 73.

During the brief time period while the contact 73-1 is open, the contact 73-2 is closed. The solenoid 201 for operating the control valve 101 is, thus, momentarily energized. A quantity of fluid is exhausted from the cylinder 98 during this period such that the receiving platform 16 is again moved downwardly by a distance equal to the thickness of the strand 11.

The limit switch actuating disc 74 is now moving along the threaded shaft 68 toward the limit switch 72 and the angular velocity of the flier tube 12 is increasing continuously to wind an additional layer of spiral convolutions in an inward direction. This is the condition of the apparatus initially described. The apparatus can now continue to function, repeating continuously the above-described cycle of operations.

Briefly reviewing the method of laying or distributing convolutions of rod in the receiver, the strand 11 is advanced continuously at constant linear speed through the exit point 86 (FIG. 2) orbited continuously about the axis of the flier tube 12 at a fixed radial distance from the axis. The angular velocity and angular acceleration of the orbiting flier are both varied continuously in the same direction of change by operation of the speed regulating apparatus 26 to lay spiral convolutions of strand on a receiver 13. The time rate of change of orbital angular acceleration is 75

also varied, through use of the auxiliary variable speed transmission 50, so as to lay the spiral convolutions in a desired compact pattern. The direction of change of these variables is reversed alternately through alternated operation of the clutches 64 and 66 to provide for the distribution of alternately inwardly spiraling and outwardly spiraling layers of convolutions. The exit point 86 and the receiver 13 are moved relatively apart vertically by a distance equal to the thickness of the strand 11 upon each such reversal, in order to preserve the desired spiral pattern in successive layers of distributed strand.

It is to be understood that the above-described apparatus and method are simply illustrative of the invention and many modifications may be made without departing from the invention.

What is claimed is:

1. In an apparatus for distributing a continuously advancing strand into spiral convolutions on a receiver: rotatable distributor means having an exit point for receiving the advancing strand and directing the strand through the exit point and toward the receiver; means for rotating said distributor means to orbit the exit point about an axis of rotation at a fixed radial distance therefrom; and speed regulating means for varying continuously both the angular velocity and the angular acceleration of said rotating distributor means in the same direction of change to direct the continuously advancing strand into spiral convolutions on the receiver.
2. An apparatus for distributing strand as set forth in claim 1, wherein said speed regulating means comprises: means for varying the rate of change of angular acceleration of said distributor means with time.
3. In an apparatus for distributing strand as set forth in claim 1:
  - means responsive to said distributor means directing the strand into a predetermined number of spiral convolutions on the receiver for reversing the direction of change of the continuous variation in the angular velocity and the angular acceleration of the rotating distributor means.
4. In combination with the strand distributing apparatus of claim 3, a receiver which comprises: means spaced apart from the distributing means by a vertical distance for receiving and supporting plural layers of spiral convolutions of strand; and means responsive to reversal of the direction of continuous variation in distributor means angular velocity for moving vertically the receiving and supporting means and the distributing means relatively apart by an additional vertical distance equal to the thickness of the strand.
5. A combination of strand distributing and receiving apparatus as set forth in claim 4, wherein said speed regulating means includes:
  - variable speed drive means having a rotating output shaft connected to the distributor means for rotating the distributor means;
  - control means operable on said drive means for continuously varying the angular velocity and the angular acceleration of the rotating output shaft; and
  - reversible operating means responsive to rotation of the output shaft for continuously operating the control means in a first direction to continuously increase the output shaft angular velocity with increasing angular acceleration and in a second direction to continuously decrease the output shaft angular velocity with decreasing angular deceleration;
 wherein said reversing means includes:
  - means responsive to a predetermined number of rotations of the output shaft for cyclically reversing the operating means to reverse the direction of continuous operation of the control means;

11

and wherein said vertical moving means includes:
means operated by the reversing means for moving
the receiving means downwardly by a distance
equal to the thickness of the strand.

6. A combination of strand distributing and receiving
apparatus, as set forth in claim 5, wherein the reversible
operating means comprise:

reversible auxiliary variable speed drive means re-
sponsive to operation of the cyclical reversing means
for continuously varying the rate of operation of the
control means with time.

7. In an apparatus for driving a coiling flier,
a first variable speed device having an output shaft;
means for driving said first variable speed device;
rotating means for operating said first variable speed de-
vice to rotate said shaft with a continually changing
angular velocity;

a second variable speed device coupled to said output
shaft for operating said rotating means at a continu-
ally changing angular velocity; and

means connecting said output shaft to drive said coiling
flier at a continually varying acceleration which is
cumulative of the effect of both of said variable speed
devices.

8. In an apparatus for distributing a continuously ad-
vancing strand into layers of spiral convolutions:

vertically movable means for receiving and supporting
layers of strand;

rotating distributor means having an exit point orbited
at a fixed radius about an axis of rotation for direct-
ing the advancing strand through the orbiting exit
point and toward the receiving means;

cyclically reversed means for varying the angular ve-
locity of the rotating distributor means to alternately
continuously increase and continuously decrease said
angular velocity; and

means responsive to cyclical reversals of the angular
velocity varying means for moving the receiving and
supporting means downwardly by a distance equal to
the thickness of the strand with each reversal.

9. In an apparatus for distributing strand, as set forth
in claim 8:

means operating upon said receiving means for vibrat-
ing continuously said receiving means during the dis-
tribution of strand.

10. An apparatus for distributing an advancing strand
into compact layers of spiral convolutions on a platform,
which comprises:

strand receiving and distributing means mounted for ro-
tation about an axis and having an exit point fixed
radially with respect to said axis for directing the
strand through said exit point and onto the platform;

variable speed transmission means for rotating the dis-
tributing means about said axis at varying angular
velocity to orbit said exit point about the axis and lay
the strand in spiral convolutions on the platform;

means responsive to the laying of a predetermined num-
ber of spiral convolutions of strand for reversing the

direction of angular velocity variation of the distrib-
uting means;

means mounting the platform and the strand distribut-
ing means for relative vertical movement therebe-
tween; and

means responsive to operation of the reversing means
for moving the platform and the strand distribut-
ing means vertically apart to lay each succeeding layer
of spiral convolutions at substantially equal vertical
distance from the strand distributing means.

12

11. A method of forming a strand continuously ad-
vancing at constant linear speed into a compact layer of
spirally convoluted strand on a horizontal receiver, which
comprises the steps of:

continuously directing the advancing strand through
an exit point spaced from the receiver and at a fixed
radial distance from a vertical axis; and
orbiting the exit point about said axis at the fixed radial
distance therefrom and at a continuously varying
angular velocity and at a continuously varying angular
acceleration, both varying continuously in the
same direction of change, to direct the continuously
advancing strand onto the receiver in spiral convolu-
tions of continuously varying radius.

12. A method of forming a compact layer of spirally
convoluted strand, as set forth in claim 11, including the
step of:

varying the rate of change of orbital angular accelera-
tion with time.

13. A method of distributing a moving strand continu-
ously advancing at a constant speed into a plurality of
layers of spiral convolutions on a horizontal receiver, com-
prising the steps of:

continuously directing the advancing strand through an
exit point spaced from the receiver and at a fixed
radial distance from a vertical axis;

orbiting the exit point about said vertical axis at the
fixed radial distance and at alternately continuously
increasing and continuously decreasing angular ve-
locity; and

moving the receiver and the exit point vertically apart
by a distance equal to the thickness of the strand
with each alternation between increasing and decreas-
ing angular velocity of orbiting.

14. A method of distributing a moving strand, as set
forth in claim 13, including the steps of:

accelerating the orbiting of the exit point at a time-
varying rate of angular acceleration during alternate
periods of increasing orbital speed; and

decelerating the orbiting of the exit point at a time-
varying rate of angular deceleration during alternate
periods of decreasing orbital speed.

15. In an apparatus for distributing an advancing strand
into compact layers of spiral convolutions on a platform,
as set forth in claim 10:

auxiliary variable speed transmission means cooperable
with said variable speed transmission means for ro-
tating said distributing means at a time-varying rate
of change of angular acceleration.

16. A method of distributing a continuously advancing
strand onto a receiver, comprising the steps of:

continuously directing the advancing strand through an
exit point above the receiver; and simultaneously
orbiting the exit point about a vertical axis and above
the receiver at a continuously varying angular ve-
locity, a continuously varying angular acceleration
and a continuously varying rate of change of angular
acceleration, said angular velocity and said angular
acceleration varying in the same direction of change.
